Primary Examiner — Robert M Spear*Assistant Examiner* — Marissa J Cash(74) *Attorney, Agent, or Firm* — Jacobson Holman, PLLC.(57) **CLAIM**

The ornamental design for a bin for aircraft storage, as shown and described.

DESCRIPTION

FIG. 1 a front perspective detail view of a bin for aircraft storage shown in an environment of use, connected together end-to-end;

FIG. 2 is a perspective view of a bin for aircraft storage; FIG. 3 is a bottom view thereof;

FIG. 4 is a top view thereof;

FIG. 5 is a left side view thereof, the right side being a mirror image thereof; and,

FIG. 6 is another perspective view shown in an open position thereof.

The broken lines in the drawings represent unclaimed environmental subject matter and form no part of the claim.
